UNITED STATES PATENT OFFICE

142,237

DESIGN FOR A SUN VISOR

Beatrice Goldberg, Brooklyn, N. Y.

Application June 14, 1945, Serial No. 120,095

Term of patent 14 years

(Cl. D57—1)

To all whom it may concern:

Be it known that I, Beatrice Goldberg, a citizen of the United States and a resident of Brooklyn, in the county of Kings and State of New York, have invented a new, original, and ornamental Design for a Sun Visor, of which the following is a specification, reference being had to the accompanying drawing, forming part thereof.

Fig. 1 of the drawing shows a perspective view

of the sun visor in open position embodying my new design;

Fig. 2 is a side view thereof; and

Fig. 3 is a plan view showing the sun visor closed ready for insertion in a pocket or case.

I claim:

The ornamental design for a sun visor, substantially as shown and described.

BEATRICE GOLDBERG.
